UNITED STATES PATENT OFFICE.

DOROTHIE BOBBÉ, OF NEW YORK, N. Y.

POWDER BOX.

Application filed September 24, 1922. Serial No. 664,347.

The object of this invention is the manufacture of a powder box adapted to contain a puff which will not be in contact with the powder, yet so arranged that the puff is easily accessible.

Fig. 1 is a perspective view of a box embodying my invention.

Fig. 2 is a vertical cross section of the box and puff shown therein.

In the figures, 1 is the box in which 2 is the base containing the powder 3, and 4 is the cover adapted to fit over the base. The top of the cover does not completely extend over it, but has a central opening 5, surrounded by a flange 6, through which the puff 7 is pressed. The puff then lies securely on a horizontal partition 8 in the cover, so that the puff is not normally in contact with the powder at all. 9 is the handle-strap by which the puff may be removed with ease.

The powder-puff is usually made of some fairly soft, spongy material and the diameter of the flange 6 is such that the puff is firmly retained thereby, yet admits of the ready extraction and placement of the pliant puff.

The article will usually be marketed complete; when it is desired to use the powder, the puff will first be removed from the flanged receptacle of the cover, and the cov-

er then taken off the box. After the powder is applied, the box is covered and the puff is then pressed underneath the flange into the puff receptacle.

The primary advantage of this construction lies in the fact that the puff being absolutely separated from the powder, except when in use, will not become laden with a superfluous amount of powder as is usually the case. This insures economical use of the powder, and it prevents the scattering of the powder, which is one of the most annoying failings of the puff carried loose in the powder-box, and yet insures a sufficient quantity being taken on the puff, instead of too little, as is the case where a sifter or a "compact" is used.

I claim:

A powder box comprising a base powder receptacle, an open topped cover fitting over the receptacle walls, and provided with a flange around its upper open rim and a transverse partition above the upper rim of the base, constituting a receptacle adapted to contain a powder puff out of contact with the powder receptacle.

Signed at New York city, in the county of New York and State of New York, this 20th day of September, 1923.

DOROTHIE BOBBÉ.
